UNITED STATES PATENT OFFICE.

JOHN P. NIKONOW, OF NEW YORK, N. Y.

SOUNDING DEVICE.

1,406,482.

Specification of Letters Patent. Patented Feb. 14, 1922.

Application filed June 29, 1921. Serial No. 481,270.

To all whom it may concern:

Be it known that I, JOHN P. NIKONOW, citizen of the United States, and resident of New York, in the county of New York and State of New York, have invented certain new and useful Improvements in Sounding Devices, of which the following is a specification.

My invention relates to the sounding devices and more particularly to the devices commonly known as "horns," in which the sound is produced by a mechanically actuated diaphragm. In my horn I am using an actuating member with variably spaced projections, so that the sound produced varies in its pitch during each revolution of the actuating drum.

My invention is more fully described in the accompanying specification and drawing in which—

Fig. 1 is a sectional elevation of my device, Figs. 2, 3 and 4 are views of modified actuating members, and Fig. 5 is a view of a device with an inclined diaphragm.

My sounding device consists of a circular diaphragm 1 with a centrally located pin 2. An actuating member or drum 3 is mounted on a shaft 4 near the pin 2. This drum has projections or teeth 5 with corresponding grooves 6 between them on its periphery. These teeth come in contact with the pin 2, when the drum 3 rotates, and the succession of rapid blows on the pin is transmitted to the diaphragm setting it in a rapid vibration, which in turn produces a sound. The pitch or tone of the sound depends on the frequency of the vibration. With closely spaced teeth a sound of a high pitch is produced, and a low pitch with larger teeth, or when they are spaced farther apart. In my device I divide the rotating drum into sectors with empty spaces 7 between. Each sector has differently spaced actuating teeth, so that in action the device produces a succession of interrupted sounds of different tones. The number of teeth in each sector may be selected according to the tone desired. For instance, by doubling the number of teeth, we get an octave. Other musical combinations may be similarly obtained.

Instead of making the teeth in each sector uniformly spaced, they may have variable pitch, as is shown in Fig. 2. In this case the device will produce a succession of sounds

of a rapidly changing tone, or the teeth may be also made of a variable size as per Fig. 3, so that not only the tone will be changed, but also its intensity. In order to facilitate the movement of the pin 2 with larger teeth, the drum surface may be made of a conical form as per Fig. 4, so that with larger teeth, the pin 2 will have a double deflection, one in a direction of rotation of the drum 3, and the other towards the small end of the cone. A similar effect may be obtained with a cylindrical drum and inclined diaphragm as per Fig. 5.

The drum may be rotated by means of a rack 8 engaging a pinion 9 on the drum. The rack is attached to a rod 10 with a handle 11 and a retrieving spring 12. The diaphragm 1 is fastened to a housing 13 with a horn 14. Instead of a manually operated rod 10 an electric motor 15 may be used.

An important advantage of my device is that it can produce sounding signals of a variable tone which can be easily distinguished from the ordinary street noises, so that this device is especially suitable for automobile horns.

I claim as my invention:

1. In a sounding device, the combination with a diaphragm, an actuating drum in co-operation with said diaphragm, said drum having a plurality of actuating sectors, and a plurality of projections on said actuating sectors, the projection on different sectors being differently spaced.

2. In a sounding device, the combination with a diaphragm, an actuating drum in co-operation with said diaphragm, said drum having a plurality of actuating sectors with smooth spaces between them, and a plurality of projections on said actuating sectors, said projections being spaced differently in different sectors, so as to produce sounds of different tones.

3. In a sounding device, the combination with a diaphragm, an actuating drum in co-operation with said diaphragm, said drum having a plurality of actuating sectors, and a plurality of projections in said actuating sectors, said actuating sectors being adapted to produce different sounds.

Signed at New York in the county of New York and State of New York this 25th day of June A. D. 1921.

JOHN P. NIKONOW.
